APPARATUS FOR PULPING PAPERMAKING MATERIAL

William V. Knoll, Dayton, Ohio

Application February 1, 1949, Serial No. 74,031

4 Claims. (Cl. 92—23)

1

This invention relates to apparatus for pulping and screening material used in the manufacture of paper.

The primary object of this invention is to provide an improved apparatus for pulping paper-making material.

Another object is the provision of an improved defibrering mechanism for use in treating paper-making material.

Still another object of the present invention is to provide an improved pulping machine having a cylindrical vessel or tank with a cone-shaped bottom portion and a beater or impeller mechanism which conforms to the cone shape of the bottom of the tank and is relatively small in peripheral dimension for operation at comparatively high peripheral velocity.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

In the drawings:

Fig. 1 is a fragmentary side elevation in vertical section, showing a batch-type of apparatus embodying the present invention.

Fig. 2 is a fragmentary side elevation in vertical section of the bottom portion of a continuous-type of apparatus embodying the present invention.

Fig. 3 is a plan view, as observed from above, of the apparatus shown in Figs. 1 and 2.

Description

The conventional types of apparatus used at present for treating paper-making material or stock are somewhat similar in design and operation and consist generally of a cylindrical vessel or tank with a rounded bottom portion or perhaps a sloping bottom portion and a flat-disk type of agitator or impeller of comparatively large diameter located near the bottom of the tank.

These relatively large disks obtain sufficient peripheral velocity, when driven at comparatively slow speeds, to cause the paper-making stock to move in a horizontal direction away from the periphery of said disks and upwardly along the sides of the vessels.

Driving these large, heavy disks at slow speed necessitates the use of cumbersome and expen-

2

sive speed-reducing apparatus in connection with the operating motor, which operates normally at a comparatively high rate of speed.

The present invention is directed to an improved type of pulping apparatus comprising a vessel or tank with a cone-shaped bottom and a relatively small agitator or impeller which conforms generally to the cone shape of the bottom of the tank and which is driven at a relatively high rate of speed to obtain the proper velocity to cause the paper-making stock to enter at the center of said agitator and be thrown violently outwardly and upwardly along the cone-shaped bottom and sides of the vessel without appreciable change of direction and without meeting undue resistance.

Applicant's improved type of impeller, which operates at relatively high speed, may be driven by direct belt connection to the operating motor, thus eliminating the heavy-duty gear reduction mechanisms used on conventional types of pulping apparatus.

The improved pulping apparatus disclosed herein preferably utilizes a cone-shaped vessel and a conforming rotor; however, it is not the desire to limit the apparatus to such shape, as it may, for example, have a rounded or dish-shaped bottom and a conforming dish-shaped rotor without departing from the spirit and scope of this invention.

Referring to the figures of the drawings, in which like reference numerals refer to like parts, the apparatus of this invention comprises a cylindrical vessel or tank 10, supported by suitable legs 11 and having an angular or frustoconical bottom portion 12, which terminates in a central neck portion 13. The opening in the neck 13 is covered by a cap 14, secured to said neck by a suitable angle piece, which encircles said neck.

Secured in the center of the cap 14 is a lower bearing housing 15, supporting a bushing in which is journaled the lower end of a vertical drive shaft 16, the upper end of which shaft is journaled in a bushing in an upper bearing housing 17, secured to a plate 18, in turn secured to an upper framework comprising parallel channel members 19 and 20 and cross angle members 21, said channel members secured to a flange 22 encircling the upper rim of the tank 10.

Secured near the lower end of the shaft 16 (Fig. 1) is a flanged hub 23, to which is secured an impeller or agitator 24, of inverted frustoconical shape, the outer face 25 of which conforms in shape to the inner surface of the coni-

cal bottom 12. The angle of the conical bottom 12 and the agitator 24, as shown, is approximately 45 degrees, which is preferable but not imperative, as the angle of these parts may be changed somewhat in either direction without detracting from or interfering with the efficient operation of the apparatus.

The shaft 16 is enclosed in a tubular sleeve 9, secured at its upper end to the bearing housing 17 and having its lower end fitting freely in a collar secured to the hub 23. This sleeve protects the shaft 16 from the twisting and accumulation of material therearound, which could conceivably interfere with the efficient operation of the device.

The disintegrating action of the agitator 24 is enhanced by a plurality of equally-spaced radial vanes 26 (Fig. 1) fast on its outside face 25 and similar radial vanes 27 fast on its inside face. The vanes 26 and 27 coact with corresponding vanes 28, equally spaced around the inside surface of the cone-shaped bottom 12 and located immediately above the upper rim of the agitator 24, to create the required turbulence and circulation of the paper-making stock to reduce it to the proper fineness for efficient paper making.

The lower end of the shaft 16 is rounded, as at 29, and said rounded surface coacts with a similar surface on a thrust piece 30, which fits freely in the lower bushing and provides means for adjusting the outer face 25 of the agitator 24 in relation to the inner face of the bottom portion 12 to secure the most efficient operation. A shoulder, formed by the reduced upper end of the shaft 16, coacts with an upper thrust collar 31, secured to the upper bearing housing 17, to limit the end play of the shaft 16.

Secured on the reduced upper end of the shaft 16 (Figs. 1 and 3) is a pulley 32, having a plurality of identical V grooves engaged by as many identical V belts 33, which engage similar grooves in a pulley 34, secured to the armature shaft 35 of a driving motor 36. The base of the motor 36 is secured to a plate 37, in turn secured to an extension of the channel member 19. A bracket 38 (Fig. 1), secured between the plate 37 and the tank 10, assists the channel 19 in supporting the motor 36, and further support is provided by a vertical post 39, extending between said motor and the floor.

The multiple V-belt drive is chosen for its simplicity and its quiet and efficient operation; however, any other suitable means of driving the mechanism may be utilized without departing from the scope and spirit of this invention.

The device shown in Fig. 1 is for so-called batch operation, in which the tank is loaded or charged and the paper-making material is treated until it is of the proper fineness and consistency for paper-making, whereupon it is drawn out of the tank through a discharge opening 45 in the neck 13, and the tank is again charged, and so on.

Fig. 2 shows the device of Fig. 1 adapted for either batch or continuous operation by providing suitable screening openings 40 in the agitator 24 and similar screening openings 41 in the angular bottom 12 of the tank 10 opposite the openings 40 in the agitator. A suitable circular chamber 42 is secured to the bottom of the tank 10 and surrounds the screening openings 41 in said tank. The chamber 42 has an outlet or discharge 43, which connects with, for example, a suitable storage place for the processed paper-making stock.

In the use of the device of Fig. 2 for continuous operation, as the paper-making material is reduced to proper fineness by the defibering action of the impeller 24, the vanes 26, 27, and 28, and the conical bottom of the tank, said material passes through the screen openings 40 in the impeller 24, thence through the opposed screening opening 41 in the conical bottom of the tank into the chamber 42, and thence out the discharge 43.

Obviously the device of Fig. 2 may be used for batch operation, if desired, by simply closing the discharge 43, charging the tank with paper-making material, as explained in connection with Fig. 1, operating the impeller 43 until the material is reduced to proper fineness, and then drawing the processed material through the discharge 43, and so on.

It will be noted that, in either the batch or the continuous type of apparatus, the agitator or impeller 24 forms a kind of vessel with angular sides, and in operation the paper-making material enters at the center of said vessel formed by said impeller and is immediately thrown violently outwardly and upwardly along the path of the cone-shaped bottom at a high velocity and without appreciably changing its direction or meeting with undue resistance. This efficient pulping action is obtained by the cone-shaped tank bottom in cooperation with the impeller, which conforms in shape thereto, assisted by the vanes 26 and 27 on said impeller and the corresponding vanes 28 on the tank bottom. Also, the shape and size of the impeller permit it to be operated at a comparatively high initial speed, thus eliminating the use of cumbersome and inefficient speed-reducing apparatus.

While the forms of mechanism shown and described herein are admirably adapted to fulfill the objects primarily stated, it is to be understood that it is not intended to confine the invention to the forms or embodiments shown herein, for it is susceptible of embodiment in various other forms.

What is claimed is:

1. In a machine of the class described, constructed and arranged for the continuous pulping of paper-making material, the combination of a cylindrical pulping tank having an inverted frusto-conical bottom, and a circular chamber formed beneath the conical bottom and connected to the interior of said tank by screening openings in said conical bottom, said circular chamber having a discharge opening; a pan-shaped agitator constructed for high-speed rotation, said agitator comprising a flat bottom portion and an integral side wall portion tapered outwardly and upwardly to match the taper of the conical tank bottom and to form an opening that is substantially larger than the flat bottom portion, said agitator being secured on the drive shaft in such a manner that the tapered side wall portion thereof is in closely spaced relationship to the conical tank bottom, said side wall portion having screening openings therein which are located opposite the similar openings in the conical tank bottom; radial vanes equally disposed on the inner and outer faces of the tapered side wall portion of the agitator; radial vanes equally disposed on the inner conical surface of the tank bottom immediately adjacent the upper edge of the tapered side wall portion of the agitator; and means connecting with the upper end of the shaft to drive said shaft and the agitator at comparatively high speed to

cause said agitator, in conjunction with the vanes, to circulate the paper-making material outwardly and upwardly to create a vortex above said pan-shaped agitator to cause the paper-making material to be drawn downwardly into said pan-shaped agitator and recirculated thereby until it becomes of proper fineness to pass through the screening openings in the tapered side wall portion of said agitator and in the conical tank bottom, and enter the circular chamber where said paper-making material is continuously drawn out of the discharge opening.

2. In an apparatus for treating paper-making material, the combination of a cylindrical tank having an inverted conical bottom therein; a drive shaft mounted vertically in the center of the cylindrical tank; a pan-shaped agitator comprising a flat bottom portion and a side wall portion secured at its downward edge to said bottom portion and tapered outwardly toward its upper edge to match the taper of the inverted conical bottom of the tank to form an opening that is substantially larger than the flat bottom portion, said agitator being secured on the drive shaft in such a manner that the tapered side wall portion thereof is maintained in closely spaced relationship with said conical tank bottom; and means to drive the shaft and the pan-shaped agitator at relatively high speed to cause said agitator to circulate the paper-making material outwardly and upwardly to create a vortex above the pan-shaped agitator, which causes the heavier portions of the paper-making material to settle into said pan-shaped agitator, where it is recirculated until it becomes the proper texture and fineness for use in making paper.

3. In a machine of the class described, constructed and arranged for the continuous pulping of paper-making material, the combination of a cylindrical pulping tank having an inverted frusto-conical bottom and a circular chamber formed beneath said conical bottom and connected to the interior of the tank by screening openings in said conical bottom, said circular chamber having a discharge opening; a pan-shaped agitator constructed and arranged for high-speed rotation, said agitator comprising a flat bottom portion and an integral side wall portion tapered outwardly and upwardly to match the taper of the conical tank bottom and to form an opening that is substantially larger than said flat-bottom portion, said agitator being secured on the drive shaft in such a manner that the tapered side wall portion thereof is in closely spaced relationship with the frusto-conical tank bottom, said side wall portion having screening openings therein which are located opposite the similar openings in the conical tank bottom; and means to drive the shaft and the agitator at relatively high speed to cause the paper-making material to be circulated outwardly and upward-

ly so as to create a vortex above said pan-shaped agitator, which in turn causes the pulping material to be drawn downwardly into said pan-shaped agitator where it is recirculated until it becomes of the proper fineness to pass through the screening openings in the side wall portion of said agitator and in the conical tank bottom, and accumulate in the circular chamber where it is continuously drawn out the discharge opening.

4. In a machine for treating paper-making material, the combination of a cylindrical tank having an inverted conical bottom therein; a shaft vertically mounted in the center of the tank; a pan-shaped agitator secured on the shaft near its lower end, said agitator being of lightweight construction for high-speed rotation, and comprising a flat closed bottom portion and an integral inverted conical side wall portion which conforms in shape to the conical bottom of the tank and is located in closely spaced relationship thereto, said agitator having a plurality of screening openings in the conical side wall portion thereof; and means operatively connected to the upper end of the shaft to drive the pan-shaped agitator at comparatively high speed to circulate the paper-making material and to cause said pan-shaped agitator to collect the circulating material as it settles in the quiet zone, near the center of the tank, and to throw said collected material outwardly and upwardly against the conical bottom of the tank to reduce said material to the proper fineness for use in making paper, which proper fineness is determined by the screening openings in the side wall of said agitator through which the properly reduced material passes.

WILLIAM V. KNOLL.
